UNITED STATES PATENT OFFICE.

ALLAN FRASER MCNAUGHTON, OF TORONTO, ONTARIO, CANADA.

WASHING MACHINE.

Application filed October 16, 1923. Serial No. 663,881.

To all whom it may concern:

Be it known that I, ALLAN FRASER MCNAUGHTON, a subject of the King of Great Britain, of the city of Toronto, in the county 5 of York, in the Province of Ontario, Canada, have invented certain new and useful Improvements in Washing Machines, of which the following is a specification.

This invention relates to a domestic 10 clothes washing machine of that class wherein the clothes are alternately squeezed against and released from the opposite sides of a sparred cage, within a water container, by the oscillation of a similarly sparred cage 15 mounted between the sides of the containing cage.

The invention is particularly described in the following specification, reference being made to the drawings by which it is accompanied, in which:

Fig. 1 is a side elevation of the washing mechanism the front wall of the tank being removed and parts of the inner and outer clothes cages being in section.

Fig. 2 is a plan of the same, half of the oscillating cage being removed.

In these drawings 2 represents the water holding tank, within which the washing is effected and which is supported in any suitable manner at a convenient height from the ground for the user. On the bottom of this tank members 3 are secured in the middle of each side, which members are notched from the upper side as at 4 to receive pins 6 projecting from the ends of a centre board 7, which extends across the bottom of the tank between the members 3:

The members 3 are also notched as at 5 to receive pins 8 projecting from the lower ends of the side members 9 of a cage frame composed of these side members with bars or rails 10 of wood extending between them, the ends of the rails being tenoned into elongated slots in the members 9.

The side members 9 are curved upward and outward from their pin-connections 8, and the lower edges of the rails project beyond the upper edges of the same, so as to offer a shouldered surface during upward movement of the clothes past them, as will be better understood later when the operation of the machine is described. A space is left between the rails sufficient to permit free passage of the water but preventing 55 passage of the clothes.

The upper end of each side member 9 has

provision at 11 for securing it to the adjacent side of the container, which securing means is removable to allow the upper edge of the cage frame on each side to be opened 60 outward, see dot and dash lines in Fig. 1, to facilitate entrance of the clothes to be washed.

The centre board 7 and the two sides 9 with their connecting rails 10, form a stationary clothes-retaining cage within the water tank 2. An oscillating shaft 12 is mounted in bearings 13 secured to the sides of the tank 2 to extend across the open top of the stationary cage 7, 9, 10.

On this shaft 12 two side frames 14 are secured immediately within the sides of the tank, between which frames a series of wooden rails 15 extend in a manner similar to the rails 9 of the stationary cage, that is, 75 the frames are provided with slot holes to receive tenons formed on the end of the rails. The outer faces of these rails have rounded edges, the upper one of which projects beyond the lower one of the same that 80 the shoulders formed by the projecting edges of the rails 15 may oppose those of the rails 10 of the stationary cage.

The shaft 12 with the inner cage 14, 15 secured on it is oscillated by a handle lever 16 85 secured on one or both ends of it, that the cage 14, 15 may be manually oscillated within the limits of the fixed cage 9, 10.

To prevent the clothes from working out from between the cages during oscillation, 90 members 17 are removably secured in the upper part of each frame 14 on each side, which members carry a rail 18 between them.

The axis of oscillation of the inner cage 95 being adjacent its upper end, and the shaft being mounted within the open top of the fixed cage, the rails of the inner cage exercise a squeezing and rolling movement on the clothes between them, and the rails of the 100 fixed cage, which movement is particularly favourable to the expression of dirt from the clothes in the presence of the water in which the operation is performed.

In use, the tank 2 being filled to the required height with hot water and a suitable detergent, the clothes to be washed are charged into one or both of the spaces between the outer railed cage 9, 10 and the inner cage 14, 15. The clothes, which tend to 110 float in the water are, during oscillation of the inner cage, alternately forced down be-

neath by the rails 18 during movement of the inner cage in one direction, and during movement in the opposite direction, the inner side of the mass of the clothes is moved 5 upward and squeezed against the rails 10 of the stationary cage, the projecting edges of which tend to hold the clothes against such upward movement, so that a rolling action occurs during the squeezing action of the 10 inner cage against the outer. In the succeeding movement in the opposite direction the downward movement of the rail 18 tends to loosen and open the mass as it is again pressed under the water.

15. The alternate loosening and rolling and squeezing actions in the water quickly and effectively cleanse the clothes.

What I claim as my invention is:

1. A washing machine, comprising in 20 combination, a tank adapted to hold water, a cage composed of spaced apart rails secured to the walls of the tank and extending between them in curved lines extending upward and outward from the bottom of the 25 tank, a shaft supported in bearings in the upper part of the tank midway between the walls of the cage, a relatively smaller inner cage secured to and downwardly projecting from the shaft to adjacent the bottom of the 30 tank, the walls of said inner cage being of spaced apart rails and parallel to those of the outer cage and similarly curved upward

and outward from the bottom, said inner cage having also a rail projecting on each side from the top over the space between the 35 outer and inner cage, and means for oscillating the inner cage.

2. A washing machine, comprising in combination, a tank adapted to hold water, a centre board removably supported across the bottom of the tank, a cage, the walls of which are composed of spaced apart horizontally disposed rails extending across between frames secured to the walls of the tank, said walls being curved upward and 45 outward from the edges of the centre board to adjacent the top of the tank, a rocking shaft extending across the upper part of the cage midway between its walls, said shaft mounted in bearings in the walls of the tank, 50 an inner cage secured to the shaft and projecting downward to adjacent the centre board the bottom and sides of which inner cage are of spaced apart rails parallel to those of the outer cage and the sides of 55 which are curved upward and outward in similar curves, removable members outwardly projecting from the upper side of the inner cage over the spaces between it and the outer cage, rails secured to these 60 outwardly projecting members, and means for oscillating the shaft.

ALLAN FRASER McNAUGHTON.
